UNITED STATES PATENT OFFICE.

FREDERICK F. FESCHAREK, OF NORTH BERGEN, NEW JERSEY.

SUPPORT FOR Porthole LIGHTS AND COVERS.

Application filed October 27, 1922. Serial No. 597,269.

To all whom it may concern:

Be it known that I, FREDERICK F. FESCHAREK, a citizen of the United States, residing at North Bergen, Hudson County, 5 State of New Jersey, have invented certain new and useful Improvements in Supports for Porthole Lights and Covers, of which the following is a specification.

This invention relates to supports for 10 porthole lights and covers of ships and windows and covers for other similar orifices and has for its main object to provide a device of the character mentioned which will be simple in construction, handy 15 in use and inexpensive in manufacturing cost.

A further object of my invention is to provide such a device which will have double 20 means for supporting such lights and covers, said double means being independently releasable from one another, thereby permitting, for instance, the closing or opening of porthole lights without disturbing the suspended or open position of the cover for 25 said porthole.

Further objects of my invention will be apparent as the specification of the same proceeds.

For a full description of the invention 30 and the merits thereof and also to acquire a knowledge of the details of construction of the same for effecting the various results mentioned hereinbefore, reference is to be had to the following description and 35 accompanying drawings.

While the essential and characteristic features of the invention are susceptible of modification, still the preferred embodiment of the invention is illustrated in the accompanying drawings, in which:—

Fig. 1 is a perspective view of my device in the double form as applied to a porthole light and cover of a ship, said porthole frame, light and cover, and a portion of the 45 ships hull being also shown but not forming part of this invention;

Fig. 2 is a front elevational view of the embodiment of my device shown in Fig. 1;

Fig. 3 is a side elevational view of the 50 same, and

Fig. 4 is another embodiment of my invention, to be used with a single porthole or other orifice covers only and showing improved means for facilitating their engagement with and release from said covers.

Referring more closely to the drawings, 5

is the hull of the ship and 6 a porthole in the same with frame 7 and locking screws and wing nuts 8. Hingedly applied to the frame 7 are porthole lights 9 having the 60 usual transparent glass plate 10 therein and the inner metal cover 11. Both light and cover have lugs 12 adapted to be engaged by the screw and wing nut 8 when it is desired to close and lock said light or said 65 cover. The numeral 13 indicates my supporting device in general and the same is suspended from the hull of the ship and at a short height above the porthole by the chain 14 or by any other suitable means. 70 In the preferred embodiment of the same as illustrated in Figs. 2 and 3, my device is composed of two single hooks 15 and 16 with a hinged joint 17 between them. The upper hook device 15 has an opening 18 at 75 its upper end to receive the suspending chain or other means for said purpose, while the lower end of the same is formed to receive the hinge device 17. Between said two ends and in the lower portion of the same, two 80 horizontally extending projections 19 are formed, preferably with upwardly curved ends 20 and designed to receive the two lugs 12 on the porthole cover 11. The lower hook device is formed in a similar manner 85 to the upper one, its upper portion being adapted to engage the hinge device 17 while the lower portion of the same is branching out into two additional projections 19 designed to engage the lugs 12 on the porthole 90 light 9. When it is desired to close both, the porthole light and cover, both the upper and lower hook devices 15 and 16, respectively, are pulled outwardly from underneath the lugs 12 and said lugs dropped into 95 engagement with the wing screw and nut 8 and locked thereafter. Usually the light 9 is open or closed while the cover 11 is steadily kept in a suspended open position, so that it is desirable to change the position of the lower hook 16 only of my device.

For this purpose, I employ the hinge device 17 which permits the movements of the lower hook 16 independently of the upper hook 15. A flat spring 21 may further be 100 secured to the upper hook 15 to steady the movement of the lower one and to keep it in the right vertical position.

In Fig. 4, I show a simplified embodiment of my device to be used with such cases 110 where the porthole is hinging on a vertical axis and it is only necessary to suspend the

porthole cover. In this embodiment, I also show two roller devices 22 applied on the branches 19 of my supporting hook and design to facilitate the co-operation of said 5 supporting device with the lugs 12.

What I claim as new and want to protect by Letters Patent is:—

1. A supporting device for porthole lights and covers of ships and the like, comprising 10 a hook device with a vertical stem and two horizontally extending branches, means to suspend said hook device, a second hook device similar to the first one and arranged underneath the same co-planarly with it and 15 a hinge device pivotally connecting the stem of the lower hook to an extension of said upper hook.

2. A supporting device for porthole lights and covers of ships and the like, comprising

two hook devices with horizontally extending branches adapted to engage said lights or covers and a hinge device pivotally connecting said two hooks; means to suspend the upper one of said hook devices; a flat spring secured to the upper one of said hook devices and engaging the lower one of the same, and rollers on said branches adapted to facilitate the engagement of said hook devices with said covers or lights.

In testimony whereof, I have signed my name to this specification in the presence of two subscribing witnesses, this 21st day of October, 1922.

FREDERICK F. FESCHAREK.
